METHOD FOR PRODUCING
LUBRICATING OIL

David R. Merrill, Long Beach, Calif., assignor to
Union Oil Company of California, Los Angeles,
Calif., a corporation of California

Application November 6, 1933, Serial No. 696,851

10 Claims. (Cl. 196—13)

This invention relates to a process for the treatment of petroleum with selective solvents. It is a continuation in part of my copending United States patent applications Serial No. 686,176 filed

5 August 21, 1933 and Serial No. 686,941 filed August 26, 1933.

In the production of lubricating oil for internal combustion motors it is highly desirable to obtain a product which exhibits a low temperature viscosity susceptibility, a low Conradson carbon residue value, a high stability towards sunlight and a low oxidation value. Crude lubricating oil fractions produced either as distillates or as residues are usually composed of mixtures of 10 paraffinic, naphthenic, aromatic and olefinic hydrocarbons. The olefinic hydrocarbons are highly unsaturated and their presence in the finished lubricating oil is undesirable because of their unstable characteristics. These compounds 15 are unstable and usually darken when exposed to sunlight. Furthermore, they have a high tendency towards polymerization with the result, after a considerable period, that these compounds are converted into resinous substances which increase 20 the sludge value of the oil.

The aromatic and naphthenic hydrocarbons present in crude lubricating oil fractions are undesirable because these compounds exhibit too great a change in viscosity for a given change in 25 temperature. The paraffinic hydrocarbons present in crude lubricating oil fractions are the most desirable materials to be employed as lubricants. These compounds are highly saturated, hence, 30 from a chemical standpoint, they are rather inactive and do not exhibit a tendency towards the formation of undesirable resinous or sludge-forming constituents. Furthermore, these compounds exhibit a low temperature viscosity susceptibility. In other words, they exhibit a minimum change 35 in viscosity for a given change in temperature. Furthermore, these highly saturated hydrocarbons are relatively stable to sunlight, exhibiting little tendency toward discoloration or sludge formation. When I use the term "paraffinic 40 hydrocarbons" I mean those compounds which are present in petroleum having the aforementioned characteristics and which are liquid at ordinary temperatures. This group of hydrocarbons does not include those compounds present 45 which are usually solid or semi-solid at ordinary temperature and which are known as "wax" or "petrolatum".

A further indication of the purity of a lubricating oil is its viscosity gravity constant. This constant represents the paraffinicity or naphthenicity

of an oil. A high value represents a high degree of naphthenicity while low values indicate relatively greater paraffinicity. Lubricating oils from natural crudes range from 0.903 viscosity gravity constant for an extreme Gulf Coast type to 0.807 5 for an extreme Pennsylvania type, or even beyond. The viscosity gravity constant referred to in this application has been determined by the method employed by Hill and Coates as set forth in the Journal of Industrial and Engineering Chemistry, 10 vol. 20, page 641 of 1928.

As a matter of convenience hereafter, I will refer to the desirable lubricating oil constituents of petroleum as the "paraffinic" hydrocarbons and to the undesirable constituents, such as olefinic, 15 naphthenic and/or aromatic hydrocarbons as the "non-paraffinic" constituents of petroleum.

In the production of lubricating oil from crude petroleum residues or distillates, it is becoming conventional in the art to separate the desirable 20 paraffinic hydrocarbons from the undesirable olefinic, naphthenic and/or aromatic compounds by the use of solvents which selectively dissolve the undesirable hydrocarbons present in the petroleum fraction but which exhibit only a very 25 limited solvent power on the desirable paraffinic hydrocarbons.

A number of selective solvents have been found desirable to separate the paraffinic from the non-paraffinic hydrocarbons, for example, it has been shown that such materials as sulphur dioxide, beta beta dichlorethyl ether, chloraniline, nitrobenzene, aniline and furfural are highly selective as the solvents for the non-paraffinic hydrocarbons. The foregoing selective solvents are relatively 30 heavy as compared to petroleum. When these relatively heavy solvents are commingled with petroleum or petroleum fractions under the proper conditions of temperature, the undesirable non-paraffinic hydrocarbons present pass into solution 35 to a greater or less extent but the desirable paraffinic hydrocarbons remain largely undissolved. If the commingled mass is allowed to remain in a quiescent state the solution of undesirable hydrocarbons and solvent settles to the bottom of the container and forms what is known 40 as an "extract" phase. The relatively light paraffinic hydrocarbons rise to the top of the vessel and form a raffinate phase. These phases are 45 then readily separable by ordinary decantation means. The raffinate phase is usually found to contain a small quantity of the selective solvent 50 and the extract phase ordinarily contains a relatively large quantity of the solvent. These fractions may be purified by subjecting them to dis-

illation whereby the solvent is distilled away from the hydrocarbon oils.

Due to the general similarity of the various hydrocarbon components of mineral oil fractions such as lubricating oils, solubilities of the undesirable, non-paraffinic fractions and the desirable paraffinic fractions in a selective solvent usually differ only in degree, and there is, therefore, a tendency for desirable, high grade paraffinic oil to be carried away with the extract resulting in a loss in the yield of paraffinic fractions obtained. In other words, in a phase separation of extract and raffinate fractions from mineral oil employing a selective solvent, an equilibrium of paraffinic components as well as non-paraffinic components is established between the phases. Consequently, some of the desirable paraffinic fraction is found in the extract instead of in the raffinate.

While some loss may occur in a primary extraction of lubricating oil with a selective solvent for the production of a low grade primary extract and a primary raffinate, the loss of desirable paraffinic fractions in the extract is especially severe when the raffinate produced by the primary extraction is further treated by a selective solvent to produce a high grade raffinate and intermediate grade extracts. In the production of a low grade primary extract and a primary raffinate in the first extraction, the difference in solubility of the respective oils is usually so great that a commercially satisfactory separation is obtainable. In some cases, however, such a process results in a substantial loss of paraffinic components in the low grade extract. The difference in solubility between the intermediate grade extracts and high grade raffinate produced by a succession of extractions is usually not so great and there is, therefore, more tendency for paraffinic oil to be carried away with the intermediate grade extracts.

It has been proposed to regulate the solvent power of the extracting agent at any stage of the treatment in accordance with the solubility of the material to be extracted and as the refining of the stock by extraction progresses in a step-wise manner, the solvent power of the treating agent may be increased.

By substantially increasing the solvent power or ease of miscibility of the treating agent, it is possible to fractionate the raffinate obtained after extraction with the pure solvent into a further extract of lower solubility than the first extract obtained by the use of said pure solvent and a second raffinate of consequently lower solubility than the first raffinate.

It has also been found desirable to first extract a hydrocarbon mixture with a pure selective solvent, for instance one of the solvents set forth above, and then to re-treat the raffinate so produced with a modified solvent. As modifying agents such materials as carbon bisulphide, xylene, benzene, toluene, carbon tetrachloride, ethers or tetrachlorethane may be employed with the selective solvent.

By these processes the oil feed is divided in one general operation into three or more fractions of different viscosity-gravity constants. As previously stated, the successive extractions produce a high grade raffinate and intermediate grade extracts characterized by solubilities which are not very different from each other. Consequently, in ordinary treatment of mineral oil by successive extractions, a substantial portion of the paraffinic fraction is soluble in the extract-solvent mixture

and is lost therein, resulting in a corresponding loss in yield of desirable high grade raffinate.

It has also been proposed to regulate the solvent power of the extracting agent at any stage of the treatment by controlling the temperature at which the extraction takes place. For instance, the temperature at which the primary extraction takes place may be relatively low in order to reduce correspondingly the solvent power of the solvent. The low grade extract thus produced may then contain substantially only the highly aromatic and most soluble fractions of the mineral oil. Subsequent to recovery of the primary raffinate from the low grade extract, the former may again be solvent extracted at a higher temperature than that which prevailed in the primary extraction. The extraction at higher temperature may be accomplished by the same solvent as that used in the primary extraction or a solvent of greater or less solvent power than that employed for the first extraction may be used for the second extraction. These successive extractions likewise produce a high grade raffinate and intermediate grade extracts having relatively similar solubilities and consequently substantial quantities of desirable paraffinic components are lost in the extract phases. Such loss also occurs when mineral oil is successively extracted with the same solvent at the same temperature.

It is an object of my invention to retain the desirable, high grade paraffinic fractions in the raffinate produced by solvent extraction of mineral oils.

I have found that the paraffinic fractions may be retained in the raffinate by rectifying the phases. This may be accomplished in a series of successive extractions by intermingling the extract phases with raffinate phases of low content of paraffinic constituents. The equilibrium established in the phase separation of these mixtures is such that the paraffinic content of these extracts tends to be re-distributed into the raffinate phase.

It is a further object of my invention to rectify intermediate extracts produced by successive solvent extractions in order to reduce their content of valuable paraffinic components and to retain these components in the raffinate.

In my applications for patent filed August 21, 1933 bearing Serial No. 686,176 and filed August 26, 1933 bearing Serial No. 686,941, I have disclosed that an oil recovered from the extract phase by cooling may be reintroduced into the extraction system for rectification purposes. Other oils may likewise be employed; for example, the oils recovered from the extract phase of a solvent extraction by totally evaporating the solvent from a portion of such extract phase, or by removing only a part of the solvent from the extract phase, or I may use an oil from an extraneous source such as liquid propane or naphtha.

The addition of these materials to an extract phase containing fractions desired in the raffinate results in rectification because, at the appropriate temperature, the solubility of the paraffinic oil in the extract phase is exceeded and some of this paraffinic oil passes into the raffinate phase by redistribution or rectification.

By the addition of propane or naphtha to the extract containing valuable paraffinic components, as well as non-paraffinic fractions and solvent, redistribution results in at least a portion of the paraffinic fraction passing from solution to form a raffinate phase.

However, such rectification is at the expense of using substantially more solvent because the added oil must also be partially redissolved, and more solvent is necessary because the oil concentration is reduced when the extract phase is finally removed from the system at a low temperature after being chilled for production of a raffinate to be returned to the system.

I have found that an economy of solvent can be obtained by removing the extract at a higher temperature. Also, by my rectification, the extract phase leaving the column contains more non-paraffinic fractions. Consequently less solvent need be used in my process.

Accordingly, it is another object of my invention to employ an economical amount of solvent in solvent extraction of oils.

Referring to the drawing, the figure is a diagrammatic view of one type of apparatus suitable for carrying out my invention.

In the apparatus shown in the figure, oil is introduced into extractor and rectifying column 10 via line 11 controlled by valve 12 by action of pump 13. Line 11 connects with orifice mixer 14 which in turn communicates with column 10 via line 15. Stock tank 16 connected with line 11 may contain unextracted fresh feed or a raffinate produced by a prior solvent extraction. In the latter case fresh feed is introduced into primary extractor 20 via line 21 controlled by valve 22 by action of pump 23. Fresh selective solvent is introduced into primary extractor 20 via lines 25 and 29 by action of pump 24. Flow through lines 25 and 29 is controlled by valves 26 and 33 respectively. In some instances, solvent from a second extraction to be described may be introduced into primary extractor 20 via lines 146, valve 33 and line 29. In the latter case, fresh solvent may or may not be introduced via lines 25 and 29, as desired. Preferably the oil in 20 is subjected to countercurrent extraction by the selective solvent, however introduced. Low grade extract and the major proportion of the solvent are removed from the primary extractor through line 27 controlled by valve 28. Primary raffinate produced in extractor 20 is removed therefrom through line 30 and valve 31 by pump 32. Line 30 connects with storage tank 16.

Extractor and rectifying column 10 is divided into a number of sections 35 to 41 by imperforate plates 42. Each section in turn is divided into a mixing zone 43 and a settling zone 44 by plate 45 provided with port 46. Each mixing zone may be provided with agitator 47 if necessary. Column 10 is preferably a vertical unit provided with sections 35 to 41 in descending order. While the feed may be introduced into any of these sections, in practicing my invention I prefer to introduce the same at some intermediate section, for instance section 37. Fresh solvent is introduced into column 10 through line 50, valve 51, orifice mixer 52 and line 53 by action of pump 54. I prefer to introduce the fresh solvent into the uppermost section 35. High grade raffinate is removed from this section by line 55 controlled by valve 56. Extract and solvent from section 35 are removed therefrom by pump 60 through line 61 controlled by valve 62 and are intermixed with a raffinate produced in a lower section of the tower, in a manner to be described. This mixture passes through line 63, orifice mixer 64 and line 65 into the mixing zone 43 of section 36. From the mixing zone the mineral oil mixture and solvent passes through port 46 into settling zone 44. The raffinate from the settling zone of

section 36 is removed therefrom by action of pump 70 and passes via line 71 controlled by valve 72 into contact with the solvent entering valve 70 via line 50.

The extract and solvent phase produced in setting zone 44 of section 36 is removed by pump 73 through line 74 controlled by valve 75. Line 74 connects with feed line 11 and the mixture of extract, solvent and feed passes through orifice mixer 14 and line 15 into mixing zone 43 of section 37 in the manner previously described. The mixture passes through port 46 into settling chamber 44 of section 37 and the raffinate separated therein is passed by pump 76 through line 77 controlled by valve 78. Line 77 joins with line 15 61 and the commingled material passes through line 63, orifice mixer 64 and line 65 into section 36 in the manner previously described.

In a similar manner the extract and solvent from section 37 and the raffinate from section 39 are removed through lines 80 and 81, valves 82 and 83 by pumps 84 and 85, respectively, and are then commingled by passage through line 86, orifice mixer 87 and line 88 prior to their entrance into section 38. Raffinate from section 38 passes through line 90 controlled by valve 91 by action of pump 92 and thence into feed line 11 with which line 90 is connected.

Extract and solvent from section 38 and raffinate from section 40 pass through lines 94 and 95, valves 96 and 97 by pumps 98 and 99, respectively, thence intermingle in line 100 and orifice mixer 101 before passage into section 39 via line 102. Extract and solvent from section 39 and raffinate from section 41 pass through lines 105 and 106, valves 107 and 108 and pumps 109 and 110 and intermingle in line 111 and orifice mixer 112 before passage into section 40 via line 113. Extract and solvent from section 40 passes through line 115, valve 116, pump 117, line 118, orifice mixer 119 and line 120 into section 41. Intermediate extract phase is removed from section 41 through line 125 controlled by valve 126 by action of pump 127 and may be entirely removed from the system by passage through line 128 and valve 129. The solvent with which it is associated may be removed by any means such as by conventional distillation.

In the above described apparatus, the solvent is introduced into an upper or primary section, such as section 35, and the oil is introduced into a lower or tertiary section. Extraction takes place in both sections and the extract phase from the upper section is commingled in an intermediate or secondary section with the raffinate phase produced in the lower section. Raffinate from the intermediate section travels to the upper section and extract from the intermediate section passes to the lower section.

Part of the intermediate extract and solvent may be by-passed from line 125 through valve 130 and line 131 for passage through cooler 132 cooled by any appropriate means. The mixture then travels through line 133 into settler 135. Sufficient cooling should be provided in cooler 132 to reduce the solvent power of the solvent intermingled with the intermediate extract to cause substantial phase separation in settler 135. Raffinate is removed from 135 through line 136, valve 137 and pump 138. Line 136 connects with line 70 and the raffinate from 135 flows with the extract from section 40 through line 118, orifice mixer 119 and line 120 in the manner previously described. The solvent contaminated with some extract separated in settling chamber 135 passes 75

via line 140, valve 141 and pump 142 into heater 145 where the solvent is heated to increase its solvent power prior to passage through line 146 which connects with feed lines 11 and 29.

5 In the operation of this apparatus, fresh, unextracted oil feed may be introduced into extractor and rectifying column 10 via line 11. In certain instances it may be desirable to maintain sections 35 to 41 at successively decreasing temperatures but it is also within the purview of my invention to maintain sections 35 to 41 at the same temperature or even at successively increasing temperatures.

It is also within the scope of my invention to 15 first extract a mineral oil in primary extractor 20 and to subject the raffinate thus obtained to a second extraction in column 10 in the manner described. The solvent employed for the second extraction may be the same as that used in the 20 primary extraction. In that case, I usually prefer to use higher temperatures in the second extraction than in the first extraction, although in some instances the same or a lower temperature than that prevailing in the primary extraction 25 may be used in the second extraction.

In order to exemplify the application of my invention to a solvent extraction process involving a pure solvent for the first extraction followed by a modified solvent for the second extraction, 30 liquid sulphur dioxide introduced through lines 25 and 29 passes countercurrently in primary extractor 20 with the incoming oil introduced through line 21. The low grade extract containing the highly aromatic fractions and the major 35 proportion of the liquid sulphur dioxide is removed from the primary extractor 20 through line 27. The primary raffinate containing a small proportion of liquid sulphur dioxide constitutes the feed for the second extraction. The 40 solvent employed for the second extraction may be modified by one or more of the aforementioned modifying agents; for instance, this solvent may comprise 70% liquid sulphur dioxide and 30% benzene. It is desirable that the high 45 grade raffinate removed via line 55 will contain substantially all of the paraffinic fractions of low viscosity gravity constant and it is also desirable that the intermediate extract removed from the second extraction via line 128 will be substantially 50 free of these valuable paraffinic fractions.

The raffinate in section 35 will contain a substantial proportion of the paraffinic components of the feed introduced into column 10 via line 11, orifice mixer 14 and line 15. Because of the 55 magnitude of the partition co-efficient of paraffinic constituents between the raffinate and extract phases in section 35, the presence of the highly paraffinic raffinate therein results in substantial proportions of the paraffinic components 60 passing into the extract phase. By intermixing the less paraffinic raffinate from section 37 with the extract and solvent from 35 containing a relatively high proportion of paraffinic materials and reextracting in section 36, at least a portion 65 of the paraffinic fractions will pass from the extract into the raffinate.

By contacting an extract-solvent mixture from an upper section of the tower with a raffinate from a lower section, a redistribution of paraffinic 70 fractions takes place. The extract-solvent mixture contains so large a proportion of paraffinic hydrocarbons and the raffinate from a lower section contains relatively so small a proportion of these hydrocarbons that when said extract 75 and said raffinate are mingled in the presence

of the solvent, sufficient paraffinic fractions pass from the extract to the raffinate to establish equilibrium between the two phases. Also, at the same time, some of the non-paraffinic fractions pass from the raffinate to the extract, resulting in a more paraffinic raffinate and a less paraffinic extract. Consequently after a succession of such steps the final extract contains the least amount of paraffinic fractions and the final raffinate contains those paraffinic fractions which are normally lost in the extract. The solvent associated with the intermediate grade extract and high grade raffinate, respectively, can be removed therefrom by distillation.

I have found that I can accomplish an economy 15 of solvent in operation of my process by by-passing part of the intermediate extract from line 125 through cooler 132 into settler 135. The temperature of the extract and solvent mixture is sufficiently reduced in cooler 132 to cause substantial phase separation in settler 135 whereby the solvent is largely freed of oil. When the raffinate from 135 passing through line 136 is intermixed with the extract from section 40 passing through line 115, an equilibrium is established 20 in section 41 to which the mixture flows, whereby the paraffinic components brought into the mixture by the extract tend to migrate into the raffinate in the manner described above.

The solvent from settler 135 contaminated with 25 a small quantity of oil has high solvent power at the proper temperature. By proper cooling it may contain less than 3% of oil. Consequently, this slightly contaminated solvent is heated in heater 145 prior to return into the system with the feed 30 introduced through line 11. While the feed may be introduced into any other section of tower 10, it is preferred to introduce the feed and re-cycled extract and solvent into the same section because the proper equilibrium between the 35 paraffinic fractions in the raffinate and the non-paraffinic fractions in the solvent is a function of the proportion of the volume of mineral oil being extracted and the volume of solvent employed for said extraction. Therefore, it is desirable to submit the relatively large volume of 40 feed directly to intermixture with the relatively large volume of slightly contaminated solvent recycled from settler 135. The return of this solvent from 135 substantially reduces the 45 amount of fresh solvent to be introduced via line 50.

As an example of the temperature conditions which may exist in the above described process, the oil may be introduced into primary extractor 55 20 at 95° F. for countercurrent extraction with 200 volume percent, liquid sulphur dioxide introduced via line 25 at 110° F. The primary raffinate thus produced may enter section 37 at column 10 at 90 to 100° F. As the raffinate rises from section to section in 10 its temperature is successively increased and the temperature in section 35 may be 120° F. As the extract descends from section to section in 10, its temperature is successively decreased and the temperature in section 41 may be 80° F. The fresh sulphur dioxide-benzene mixture introduced via line 50 may be 250 volume percent. of the original oil feed. In order to produce adequate phase separation of the intermediate extract and solvent in settler 135 this 70 mixture may be cooled to 20° F. The extract thus obtained together with the solvent, may be heated to 100° F. or more in heater 145 prior to intermixture with the fresh feed to the column 10.

In some instances I may desire to employ the 75

same solvent in both the primary and secondary extractions, and at the same time utilize the solvent power of the contaminated solvent obtained in settler 135. Accordingly, all of the intermediate 5 extract from column 10 passing through line 125 is caused to travel, together with the solvent contained therein, through cooler 132 and line 133 into settler 135 wherein phase separation occurs. As previously described, the raffinate thus produced passes from settler 135 via line 136 to intermingle with the extract from section 40 prior to introduction to section 41. The solvent removed from settler 135 travels via line 140, valve 141 and pump 142 through heater 145, line 146, 10 valve 33 and line 29 into primary extractor 20 for countercurrent extraction with incoming feed entering through line 21.

When the same solvent is used in both extractions, the amount of solvent introduced into the 20 system through line 50 will preferably be controlled in such manner that the primary extract issuing from extractor 20 via line 27 will have the desired predetermined viscosity gravity constant. Ordinarily, according to this operation, no additional fresh solvent is necessary for the first extraction and consequently valve 26 in line 25 will remain closed.

The temperature of the contaminated solvent 30 from 135 may be raised sufficiently in heater 145 so that the temperature of the primary extraction is suitable for dissolving the desired amount of low grade constituents. With 200 volume percent. of solvent comprising 30% benzene and 70% 35 liquid sulphur dioxide, a temperature of 30° F. would frequently be suitable. With the exceptions set forth above, the sequence of steps for solvent extraction using the same solvent in both extractions is the same as that for the described 40 method of extraction employing a different solvent in the primary extractor 20 than in the column 10.

It is to be understood that the foregoing is merely illustrative of the generic invention, and the examples are not to be taken as limitations 45 thereof, as many modifications of my invention may be made within the scope of the following claims:

I claim:

1. A process for the separation of paraffinic and non-paraffinic fractions from an oil containing the same which comprises extracting said oil with a selective solvent, separating a primary raffinate insoluble in said solvent from a low grade extract soluble therein, introducing a selective solvent into a primary stage of a second extraction system, introducing said primary raffinate into the tertiary stage of said system, introducing a paraffinic oil fraction and selective 55 solvent in said primary and tertiary stages respectively of said second extraction system, removing a raffinate from the primary stage and extract from the tertiary stage and at a secondary stage of said second extraction system commingling extract phase from the primary stage with raffinate from the tertiary stage.

2. A process according to claim 1 in which the selective solvent for the second extraction is a modified selective solvent.

3. A process according to claim 1 in which the temperature in the primary stage of the second extraction system is higher than the temperature in the secondary stage and the temperature in the secondary stage is higher than the temperature 70 in the tertiary stage.

4. A process for the separation of paraffinic and non-paraffinic fractions from an oil containing the same which comprises extracting said oil with a selective solvent, separating a primary raffinate insoluble in said solvent from a low 5 grade extract soluble therein, introducing a selective solvent into a primary stage of a second extraction system, introducing said primary raffinate into the tertiary stage of said system, removing a raffinate from the primary stage and extract from the tertiary stage, at a secondary stage of said second extraction system commingling extract phase from the primary stage with raffinate from the tertiary stage, separating extract phase and raffinate at said secondary stage, 10 introducing said last mentioned raffinate into the primary stage and said last mentioned extract phase into the tertiary stage.

5. A process according to claim 4 in which the selective solvent for the second extraction is a 20 modified selective solvent.

6. A process for the separation of paraffinic and non-paraffinic fractions from an oil containing the same which comprises extracting said oil with a selective solvent, separating a primary 25 raffinate insoluble in said solvent from a low grade extract soluble therein, introducing a selective solvent into an upper stage of a second extraction system, introducing said primary raffinate at a lower stage of the system, introducing 30 a paraffinic oil fraction and selective solvent in said upper and lower stages respectively of said second extraction system, removing a raffinate from the upper stage and extract from the lower stage and at an intermediate stage commingling 35 extract phase from the upper stage with raffinate from the lower stage.

7. A process for the separation of paraffinic and non-paraffinic fractions from an oil containing the same which comprises extracting said 40 oil with a selective solvent, separating a primary raffinate insoluble in said solvent from a low grade extract soluble therein, introducing a selective solvent into an upper stage of a second extraction system, introducing said primary raffinate at a lower stage of the system, removing 45 a raffinate from the upper stage and extract from the lower stage, at an intermediate stage contacting extract phase from the upper stage with raffinate from the lower stage, separating 50 extract phase and raffinate at said intermediate stage, introducing said last mentioned raffinate into the upper stage and said last mentioned extract into the lower stage.

8. A process according to claim 7 in which the 55 temperature in the upper stage of said second extraction system is higher than the temperature in the intermediate stage and the temperature in the intermediate stage is higher than the temperature in the lower stage.

9. A process for the selective solvent extraction of mineral oils at different temperatures which comprises extracting said oil with a selective solvent, separating a primary raffinate insoluble in said solvent from a low grade extract 65 soluble therein, introducing a selective solvent into an extraction zone of relatively high temperature, introducing said primary raffinate into an extraction zone of relatively low temperature, removing high grade raffinate from the high temperature zone and intermediate grade extract from the low temperature zone, at a zone of intermediate temperature contacting extract phase from the high temperature zone with raffinate from the low temperature zone, separating ex- 70 75

- tract phase and raffinate from said intermediate temperature zone, introducing said last mentioned raffinate into the high temperature zone and said last mentioned extract phase into the low temperature zone. 5
10. A process for the separation of paraffinic and non-paraffinic fractions from an oil containing the same which comprises extracting said oil with liquid sulphur dioxide, separating the raffinate insoluble therein from the extract phase, subsequently extracting said raffinate with liquid sulphur dioxide modified by benzene, separating the raffinate insoluble in said liquid sulphur dioxide and benzene from the extract phase comprising dissolved fractions, chilling said last mentioned extract phase to reject an insoluble fraction therefrom, separating said rejected insoluble fraction from said extract phase, and returning said rejected fraction to said second mentioned extraction for treatment with liquid sulphur dioxide modified by benzene. 10

DAVID R. MERRILL.
